UNITED STATES PATENT OFFICE

THURLOW E. McFALL, OF SPARTA, MICHIGAN

PISTON RING ARBOR

Application filed February 26, 1930. Serial No. 431,352.

This invention relates to a piston ring casting sawing machine and arbor for holding a plurality of the piston ring castings in position to be acted upon by a plurality of saws, for the purpose of splitting the rings substantially midway between their opposite flat sides and thereby making two narrower ring castings from each of the ring castings placed on the arbor. I have heretofore made application in the United States Patent Office for a process of piston ring casting, said application having Ser. No. 344,373 filed March 5, 1929, which was allowed December 20, 1929 and has become Patent No. 1,749,147. The process of piston ring casting disclosed in said application contemplates using a pattern for ring castings of twice the width, plus allowances for shrinkage and machining of the piston rings which are to be manufactured, and after the ring castings have been produced from the pattern, splitting or dividing each casting substantially midway between its opposite flat sides to thereby obtain from each of the original double width piston ring castings two ring castings of narrow width, of uniform character of metal throughout and with a complete elimination of hard spots of metal therein which are prevalent in individual ring castings for the narrow width rings now almost universally used in internal combustion engines; and at the same time the two ring castings which are produced from each of the double width ring castings, after the process of splitting has been carried out, are produced at a cost but very little if any greater than one of the narrow width ring castings when the same are produced individually. The present invention is directed to a very practical and efficient mechanism including a ring casting holding arbor whereby the ring castings of double width are readily split or cut substantially midway between their flat sides, a plurality of the ring castings being operated upon simultaneously by a plurality of metal cutting saws thereby effecting the ready division or splitting of the double ring castings each into two narrower width ring castings of the size desired for piston rings. The invention further con-

templates a novel construction of arbor for holding the double width ring castings in proper relation to each other and against movement on the arbor during the time that the sawing operation is taking place. Many other objects and purposes than those stated will be apparent upon understanding of the invention had from the following description, taken in connection with the accompanying drawings, in which,

Fig. 1 is a fragmentary front elevation, partly in section, illustrative of a machine for splitting a plurality of double ring castings each into two parts.

Fig. 2 is a fragmentary side elevation thereof.

Fig. 3 is an enlarged longitudinal vertical section through the expanding ring casting holding arbor of my invention, showing the arbor in collapsed condition.

Fig. 4 is a view similar to Fig. 3 showing the arbor expanded to engage and hold the ring castings.

Fig. 5 is an end elevation of the arbor on a still larger scale.

Fig. 6 is a fragmentary elevation of one end portion of the arbor.

Fig. 7 is an enlarged transverse vertical section through the arbor showing a ring casting around the same before the arbor is expanded.

Fig. 8 is a view similar to Fig. 7 illustrating the arbor expanded to hold the ring casting and the way in which a cutting saw operates with respect thereto.

Fig. 9 is a fragmentary enlarged longitudinal section through one of the members of the arbor, showing how the bottoms of the ring castings holding grooves may be lined with antislip material, such as rubber, and

Fig. 10 is a perspective view of a ring casting of the type which is to be split on the machine and of the kind shown, described and claimed in another pending application for patent filed by me of even date herewith.

Like reference characters refer to like parts in the different figures of the drawings.

The machine for splitting the ring castings may comprise a vertical support 1 at the

front side of which is a second vertical support 2 carrying a transverse guide member 3 with inclined side guides 4 at its opposed edges, upon which a horizontal table 5 is mounted for sliding movements, the table 5 having cooperating downwardly extending guides 6 to engage with the guides 4, as shown in Fig. 2, whereby the table may be moved back and forth in a horizontal plane.

10 A heavy supporting arm 7, preferably of cylindrical form, is rigidly secured at one end to the upper end of the support 1 and extends horizontally therefrom over the table 5. At its outer end it carries a downwardly extending arm 8 which in turn, near its lower end, is equipped with a suitable center 9 similar to a lathe tail stock center. A horizontal shaft 13 extends through the support 1 below the overhead support 7 and is journaled in the support 1 and its outwardly extending end is supported on the center 9. The shaft 13 is provided within the support 1 with a suitable driving pulley 11 around which a drive belt 12 passes by means of which the shaft 13 is rotated (see Fig. 1). This part of the structure is similar to a conventional milling machining construction.

In this machine the shaft 13 constitutes 30 a saw arbor on which a plurality of circular metal cutting saws 15 are mounted, the saws 15 being held in spaced apart relation by spacing collars 16 interposed between them and the saws and spacing collars are 35 fixed to the arbor shaft 13 in a suitable conventional manner. The saws 15 and spacing collars 16 may be removed for sharpening or for replacement with others of different sizes by backing off the center 9 and swinging 40 the lower end of the arm 8 to one side clear of the forward end of the arbor shaft 13 from the forward end of which shaft the saws and spacing collars may be readily removed and replaced.

45 On the table 5 near each end thereof a head stock 17 is rigidly secured near the rear edge of the table while, similarly, near the front of the table and adjacent each end a tail stock 18 is rigidly secured. Each of the 50 tail stocks is provided with the usual adjustable tail stock center 19. A shaft 20 extends through and is rotatably mounted in each of the head stocks 17 and it is between the two head stocks and the two tail stocks that the 55 ring holding arbors of my invention are to be mounted for sawing double thickness ring castings carried thereon.

In the construction of the ring holding arbors a circular plate 21, similar to a lathe 60 face plate and through which a plurality of adjusting screws 22 pass, is pinned or otherwise secured on a central shaft 23 of the arbor which, at one end portion, or that end near which the plate 21 is secured, is flattened 65 as indicated at 23a so that it may be detach-

ably connected with and driven from the head stock shaft 20, the opposite end of the shaft 23 being engaged by the pointed end of the tail stock center 19. The shaft 23 at a plurality of points between its ends, two 70 being shown, is formed with integral conical enlargements 24. Near the end of the shaft 23 which engages with the tail stock center, a circular plate 25 having a central sleeve 25a is passed over the shaft and may be secured thereon against rotating movement by a key screw 26 threaded therethrough and at its inner end seating in a keyway slot in the shaft 23. The end portion of the shaft 23 is threaded for a binding and adjusting 75 nut 27 which comes up against the outer face of the member 25. At the inner side or face of the member 25 a plurality of pins 28 project for engagement with the adjacent ends of the outwardly movable parts or sections 80 29 of the expanding arbor, each of said sections 29 at the end thereof adjacent the member 25 being slotted, as indicated at 28a, for the reception of the pins 28 (see Fig. 6).

A plurality of outwardly movable arbor 85 members 29 are located around the shaft 23 and the conical enlargements thereon. In the construction shown four of these members 29 are used and are, at their outer surfaces, shaped substantially in the arc of a 90 circle. Each at its inner side has a plurality of ribs 30 with conical inner surfaces to fit against and cooperate with the conical surfaces of the parts 24 on the shaft, whereby on relative longitudinal movement of the 95 shaft and member 29 with respect to each other in one direction said members 29 are forced outwardly. Each of the members 29 at each end thereof adjacent the plate 21 is somewhat enlarged and grooved, as indicated 100 at 31, so that when all four of the members are located around the shaft a continuous coiled spring tension band 32 may be seated in the groove, the tendency of which is to cause the arbor members to hug snugly 105 against the conical enlargements 24. The opposite end likewise has a grooved section 33 the exterior diameter of which is less than the diameter of the grooved end section 31 and in which a second continuous coiled 110 spring bank 34 is seated.

The outer surface of each of the members 29 has a plurality of spaced apart transverse flanges 35 extending therefrom defining 115 grooves each of which in the four arbor sections around the shaft 23 is adapted to receive a double width piston ring casting. The grooves at their lower middle portions are further provided with narrower grooves 36 120 the purpose of which will hereafter be described.

At one radial side of one of the members 29 a flat plate 37 is attached, the outer edge of which extends a short distance outward 125 beyond the bottoms of the grooves between 130

the flanges 35. It likewise, at spaced apart points, is formed with notches 36a in conjunction and alinement with the narrower grooves 36 in the arbor sections 29, and the bottoms of the notches 36a reach to the bottoms of said narrower grooves 36.

Each of the double ring castings 38 at one point at its inner side is formed with a transverse notch or groove 39 (see Fig. 10). When the arbor is in collapsed condition, as in Fig. 3, a plurality of the ring castings 38 may be placed over the arbor and when so placed the plate 37 should be positioned vertically as shown in Fig. 7, while the notches or grooves 39 at the inner sides of the ring castings are to be located directly over the upper edge of the plate 37 so that as the ring castings drop by gravity between the flanges 35 the upper edge of the plate 37 enters the notches or grooves 39 therein. Then by screwing the nut 27 on the end of the arbor shaft 23 from the position shown in Fig. 3 to that shown in Fig. 4, the incline faced ribs 30 on said arbor sections 29 ride upon the larger diameter portions of the conical sections 24 of the shaft 23, moving the arbor sections outward and stretching the springs 32 and 34. The outward movements of the arbor sections are guided through the pins 28 seating in the grooves 28a as shown in Fig. 6.

The extent to which the expanding arbor sections 29 may be moved outwardly is governed by the position of the screws 22 against which the ends of said sections 29 eventually come after which further outward movement of said arbor sections is stopped. The screws 22 by test, trial and experiment are properly set so that when the parts 29 abut there against the rings are seated in the grooves between the flanges 35 and the bottoms of the grooves bear tightly and firmly against the inner curved sides of the ring castings. It will be noted that even when the arbor is in its collapsed condition, as shown in Fig. 3, the ring castings cannot pass over the enlarged end parts 31 of the expanding arbor sections 29 but that the same may pass freely over the smaller ends 33 of said parts 29.

The flanges 35 serve to accurately space the double width ring castings 38 so that the saws 15 may be brought thereto and split the ring castings substantially midway between their opposite flat sides. The saws pass through to the inner sides of the ring castings and enter the grooves 36 and the notches 36a in the plate 37 as shown in Fig. 8. The saw cut is indicated at 40, in dotted lines, in Fig. 10. If for any reason it is desired that the rings be held with a greater frictional engagement at their inner sides, this can be accomplished by lining the bottoms of the grooves with rubber linings, as indicated at 41 in Fig. 9, the lining for each groove being in two parts one at each side of where the cutting saw 15 will pass through the double width ring cast-

ings 38 dividing each of the ring castings into narrower ring castings 38a as shown in Fig. 9.

A sprocket 42 is mounted on a stud shaft 10 directly above the arbor shaft 13 and close to the support 1 of the machine, the stud shaft 10 being fixed to and extending from said support 1, and the sprocket 42 is rotated through gears 14 from the arbor shaft 13. The rear end of each of the shafts 20 is provided with a sprocket 44 and a sprocket chain 43 passes around both of said sprockets 44 and also the sprocket 42 whereby the shafts 20 are rotated by and simultaneously with the arbor shaft 13. The proper direction of rotation of the shaft 20 with relation to the direction of rotation of the shaft 13 is obtained by the insertion of an idler gear in the train of gears 14 and the speed ratio of rotation between the shafts 20 and the arbor shaft 13 is properly governed by the ratios of the gears 14 and the sprockets 42 and 44. It is conceived that clutches may be utilized to connect or disconnect the sprockets 44 with their respective shafts 20 whereby one of the shafts may remain stationary while the other is being rotated and vice versa. This mechanism is not disclosed and forms no part of the present invention.

With one of the expanding arbors loaded with double width ring castings 38 the table 5 may be moved from the dotted line position shown in Fig. 1 to the full line position moving the ring castings underneath the saws 15 for splitting the ring castings midway between their opposite flat sides. While such operation is taking place with respect to ring castings on the arbor brought underneath the saws another arbor loaded with ring castings may be entered between the head stock and tail stocks mounted on the table 5 at the left hand side. Thereafter the table may be moved back from the full line to the dotted line position shown in Fig. 1, sawing the ring castings on the last mentioned arbor while those which have been split will be removed and another arbor loaded with double width ring castings put in place; and it is during this operation of inserting and taking away the arbors from the machine that the clutch drive between the sprocket wheels 44 and the shafts 20 will be used.

The machine itself of course may be equipped with suitable driving mechanism for moving the table back and forth and with reversing mechanism for automatic reversal of movement of the table and the like, all of which are very old and well known, but so far as the present invention is concerned the table 5 may be moved in any manner, for instance, by hand. The construction described is very practical for the purposes for which it has been designed and has so proved in practice. Large quantity production in the mat-

ter of splitting or dividing double width ring castings into ring castings of one-half the width of the double ring castings is accomplished through the invention which I have made. The invention is defined in the appended claims and is to be considered comprehensive of all forms of structure coming within their scope.

I claim:

1. In a construction of the class described, a horizontal shaft, a plurality of arbor members around the shaft lengthwise thereof, interengaging means between the shaft and the inner sides of said arbor members for moving said arbor members radially outward on longitudinal movement of said members in one direction along the shaft, a plurality of transverse flanges around the outer sides of said arbor members defining grooves between the flanges for the reception of the piston ring castings, each of said arbor members at the bottom of each groove therein between two adjacent flanges and midway between said flanges having a much narrower groove cut therein, and a flat metal plate secured to a radial side of one of said arbor members having its outer edge extending a short distance beyond the bottoms of said first mentioned wider grooves and having notches therein in alinement and conjunction with the narrow grooves in said members at the bottoms of the wider grooves.

2. In a construction of the class described, an arbor shaft having a plurality of spaced conical enlargements thereon, a plate attached to the shaft toward one end thereof, adjusting screws threaded through the plate, a plurality of inwardly and outwardly movable arbor members around the shaft each having a plurality of ribs at its inner side with inclined sides to cooperate with and engage against the surfaces of the conical enlargements on the shaft, means on said arbor members in which ring castings may be located, a second plate slidably mounted on the opposite end portion of the shaft, a nut threaded on said opposite end portion against said plate for moving said arbor members toward the adjusting screws carried by the first plate and bring their ends against the ends of said adjusting screws and thereby move the arbor members outwardly against ring castings located around it and stop said movement at a predetermined point, said arbor members having slots therein, and pins rigid with said second plate extending into said slots for the purpose described.

3. A construction of the class described comprising, a shaft having a plurality of spaced apart enlargements thereon of conical form, a plurality of arbor members located around the shaft in spaced relation and having at their inner sides cooperating inclined sides of circular conical form to engage against said conical enlargements on the shaft

whereby circumferential and axial movement may be had therebetween, means on said members defining grooves wherein ring castings may be located and means for moving the shaft and said members longitudinally with respect to each other to force said grooved members outwardly and thereby seat the ring castings in the grooves of said members and hold said castings against movement with respect thereto.

In testimony whereof I affix my signature.

THURLOW E. McFALL.
